CONVEYING AND SUPPORTING
MECHANISM

Henry A. Drefein, Chicago, Ill.

Application December 18, 1933, Serial No. 702,866

12 Claims. (Cl. 263—6)

This invention relates to conveying and supporting mechanism, primarily it contemplates in association with a pack heating or other furnace, for example, reciprocable conveying members, such as bars, with which intermittently actuated lifting and supporting members coact.

In the form illustrated, the movement of the conveyor members is such that a portion sufficient to receive a charge of packs or other material will project from one end of the furnace or the other at each limit of travel, so that in one position charging is possible, and in the other position the heated pack or other material may be removed for subsequent treatment. In the movement from this discharging position back to charging position, the lifting and supporting members function to raise and support the other packs above the conveying means until the return movement is completed, when the material is again deposited upon the conveying means.

Coacting with the above described apparatus, is driving apparatus by which operative movement is transmitted to the conveying means and to the supporting means. This includes a tension means together with mechanism whereby at least a large portion of the tension acting upon the driving means for the conveyor is relieved, pending the initiation of the return movement of the conveyor members.

My invention also includes other details and subcombinations which are more fully described below and shown in the accompanying drawings, in which

Fig. 1 is a vertical section through a furnace illustrating an embodiment of my invention applied thereto;

Fig. 2 is a horizontal section of the same;

Fig. 3 is an enlarged detail of a portion of the conveying and supporting mechanism;

Fig. 4 is a plan view of a portion of one of the conveyor members, parts being broken away for clearness;

Fig. 5 is an enlarged sectional detail taken along the line 5—5 of Fig. 2;

Fig. 6 is a vertical section along the line 6—6 of Fig. 5;

Fig. 7 is a vertical section drawn to an enlarged scale along the line 7—7 of Fig. 1;

Fig. 8 is a diagrammatic view of controlling means for the furnace illustrated and described, portions of the furnace, conveyor and accessory apparatus being included for convenience; and

Fig. 9 is a side elevation of a detail of one of the limit switches and actuating means.

Like numerals refer to like elements throughout the drawings.

10 designates generally a pack heating furnace having a refractory top 10a and bottom 10b, together with the usual side walls 10c, 10d. I have illustrated a combustion and heating chamber 10e located on one side of the furnace (see Fig. 2), the same forming no separate part of my present invention. A suitable burner 9 is provided at one end of the combustion chamber 10e, being illustrated as adapted for the use of gaseous fuel, although obviously any suitable fuel supply and burning means may be utilized.

The ends of the furnace 10 are provided with the openings 10f, 10g, respectively, the former being the discharge opening and the latter the charging opening.

At each end of the furnace proper is provided a vertically movable door 11 mounted to lie adjacent the upper surface of the conveyor, described below, when in closing position. Any suitable type of door operating means may be utilized, but I have illustrated an operatively satisfactory form in Fig. 1, for example, where the door 11 suitably guided for its vertical movement is connected through a flexible chain or cable 11a to a segmental pulley 11b in turn mounted upon a cross shaft 11c. Extending outwardly from the cross shaft is the arm 11d carrying a counter-weight 11e. An air cylinder 11f is provided with suitable inlet and outlet pipe 11g. Extending vertically upward from a piston 11h (see Fig. 3) is a piston rod 11i pivotally attached to the arm 11d. When air is admitted to the cylinder 11f the arm 11d is depressed and the chain 11a or flexible driving member is partially wound upon the rotating segmental pulley 11b to raise the door, as will be obvious. Cut-off of the air supply to the cylinder 11f will permit the piston and associated apparatus to return to door closing position. The same apparatus is illustrated as applied to the door at the charging end of the furnace, although this door may be omitted if so desired.

Upon the floor 10b of the furnace are supporting blocks 12 extending transversely thereof as illustrated in Fig. 2, for example. Mounted upon the supporting blocks 12 and secured thereto are the bearing brackets 13, in which are journaled rollers 14, as illustrated in Figs. 3 and 7, for example. These rollers 14 are preferably flanged at the edges, as indicated by numeral 14a, for a purpose hereinafter described. Conveyor members or bars generally indicated by numeral 15 are supported upon the flanged rollers 14, there being a plurality of these conveyor members

- mounted in parallel and spaced relation. Each of these conveyor members is preferably formed of articulated links 16, the links being illustrated as of I-section, each link 16 having an extended 5 flat tongue 16a at one end slightly offset to engage between the top and bottom flanges of the adjacent bar to which it is pivotally connected by pin 17 (see Fig. 3). In this manner an articulated conveyor member is formed of substantially straight line construction. The lower flange 10 of the conveyor link 16 moves between the flanges 14 of the rolls and substantial lateral movement is thereby prevented, as will be obvious.
- Preferably I construct the links 16 and locate 15 the rolls 14 in such manner that when the mechanism is in the position illustrated in Fig. 2, for example, i. e., what I term "charging position", or in its other rest position, i. e., "discharging position", each link will be directly supported by 20 one of the rollers at a point nearer one of its ends than the other. I calculate these points as about 18% of the total length from the nearer end. When properly supported in this manner, a maximum of support and a minimum of deflection due to superimposed loads will result, 25 as will be apparent to those skilled in the art upon calculation of moments and stresses. The end of each conveyor member 15 at the discharge end of the furnace has attached one end 30 of a chain 20, which moves over and is engaged by the sprocket 21 (see Fig. 1), thereafter passing partially around an idler 22. The opposite end of this chain 20 is attached to a cable 23, the other 35 end of which it attached to the opposite end of the corresponding conveyor member 15. Each of these cables 23 passes partially around an idler 25 and thence partially around a tensioning roller 26, and thereafter partially around a second idler roller 27.
- 40 A driving motor is provided, generally illustrated by numeral 29, which through a speed reducing gearing diagrammatically illustrated and designated by numeral 30, drives a shaft 31. Upon this shaft 31 are mounted for rotation there- 45 with, the sprockets 21. Control means hereafter described are provided for the motor 29. When the same is actuated to rotate the sprockets 21 the conveyor members 15 are moved from charging position, illustrated in Fig. 1, to discharging position or toward the left. This movement follows movement of the doors to opening position and positions a heated metal pack or other object for removal or transfer to other treatment apparatus by the operator, and while this operation is being carried on the doors may be permitted to close. Subsequently, through control means, also described below, a reversal of the conveying means is effected, as will be more fully 55 described.
- 60 Prior to the movement to discharging position when in normal use, a fresh pack, for example, is charged upon the end of the conveying apparatus which protrudes from the charging opening, consequently means must be provided to prevent return movement of the load upon the entire length 65 of the conveyor during its return movement, as otherwise there would be no provision for further charging and no relative advance of the heated packs toward discharging position. Therefore, I provide a lifting and supporting apparatus which 70 raises the packs, or other material in the furnace, above the conveying apparatus, and supports the same in such position during return movement of said apparatus. To accomplish this I provide supporting bars, generally indicated by nu- 75
- meral 35, each formed of a plurality of links 36 loosely connected to permit expansion and contraction, and generally similar in construction and arrangement to the links 16 of the conveyor bars 15. These supporting bars 35 are located in the spaces between the conveyor bars (see Fig. 7), and are mounted upon blocks 37, which in turn are carried upon cross beams 38. These cross beams are located between the transverse supporting blocks 12, as illustrated in Figs. 1 and 10 2. Supporting rods 39 shown as two in number, although the number may be varied as desired, extend from beneath the beams 38 through suitable apertures in the hearth or floor of the furnace, and through guide plates 40, 41, forming 15 the ends of guide cylinders, the bodies of said cylinders being enlarged to provide ample clearance around the rods 39. At their lower ends, these rods are supported upon longitudinal beams 43. The bars 35, blocks 37 and beams 38 are so dimensioned that when the longitudinal beams (as will be more fully explained) are lifted a sufficient amount, the bars 35 will project above the horizontal plane of the upper webs of the conveyor bars 15, and will pick up and support 20 the packs, or other load, formerly resting upon said conveyor bars. Secured to the substructure of the furnace are short beams 45, on which are mounted bearings 45a, in which bearings are 25 journaled shafts 46a carrying bell cranks 46. One extremity 46b of each of these bell cranks 46 is pivotally secured to a rod 47, which in turn is secured to a cross-beam 48 engaging the longitudinal beams 43.
- 30 A connecting rod 50 extends between and is 35 pivotally connected to the ends 46b of bell cranks 46 providing parallel motion for the respective bell cranks 46 and beams 43. At one end of the connecting rod 50 is pivotally attached a radius rod 51, the point of pivotal engagement 51a being 40 illustrated as intermediate the ends of the radius. At its upper end and at 51b, the radius rod is suitably pivoted at a fixed point substantially in the horizontal plane of the pivotal points of the bell cranks 46, as illustrated in Fig. 1. At its 45 lower end at 51c, the radius rod is pivotally attached to a connecting rod 55, which in turn is pivotally attached at 55a to the crank 56a of a motor 56. I have illustrated this motor as being associated with a suitable speed reducing gearing. It will be apparent that when the motor is actuated to rotate the crank 56a in the direction indicated by the arrow in Fig. 8, the beams 43 will be lifted during the first half revolution of the crank. Suitable control mechanism is also 55 provided for control of the actuation of this lifting motor and associated apparatus, and the same will be more fully described hereinafter. For the tensioning of each cable 23 and driving chain 20, I provide a pair of weights, the one 64 being relatively light and the other, 65, being relatively heavy. The former weight is attached to a yoke 64c, which in turn is supported upon and rotatable to the shaft of a corresponding pulley 66 as 60 illustrated in Fig. 6. Depending from each of the weights 64, is a rod 64a, having a nut 67 or head thereon. This rod 64 extends through a cap 68 upon the casing or container which forms a part of weight 65. I have illustrated this weight as being arranged for addition to or subtraction 65 therefrom and variation in such way as desired.
- 65 Each of the weights 65 is provided with a pair of upwardly projecting straps 69, which are merged at the top to form, in effect, a bail embracing and spaced from the smaller weight 64 70 75

and slotted at 69a to permit protrusion of the ends of the corresponding shaft of pulley 26. At the upper end is provided a threaded stem 69b, which extends through an aperture 70a and the arm 70b of a bell crank 70. A sleeve 69c is provided around a threaded portion of stem 69b to protect it from abrasion by the bell crank arm 70b. Threaded upon the stem 69b is an adjusting nut 69d between which and the bell crank 70 is provided a cushioning spring 72, as illustrated in Fig. 5. Each of these bell cranks is pivoted upon a cross shaft 74 suitably supported at its ends. A connecting rod 75 is provided for each of the bell cranks 70, being in pivotal engagement with the lower end of arms 70c thereof. A slot 75a is provided for this connection to insure lost motion during a portion of the reciprocation of the rods 75, which at their other ends are pivotally connected to the cross rod 59 which in turn engages rods 50 and 51.

It will be apparent that when the rods 75 are in the position illustrated in Fig. 1, the bell cranks 70 will have been actuated to lift the bars 60 and thereby to have lifted the weights 65 from dependence upon the rods 64a, and weights 64, sufficient clearness being provided beneath the cap 65a to permit this movement as illustrated in Fig. 6.

When the crank arm 56a has moved one half revolution in the direction of the arrow in Fig. 8, the weights 65 will be permitted to drop until they engage the nuts 64b, after which further movement of the rod 75 is permitted by means of the slots 75a. When this action has occurred, the combined weight of weights 64 and 65 is exerted upon the corresponding yokes 64c and in turn upon the cables 23. When, however, the crank 56a is in the position illustrated in Fig. 1, the weight 65 is lifted and the only tension upon cables 23 is that due to weight 64.

The purpose of the apparatus just described is to relieve the conveyor bars of the maximum tension from the cables and chains, except during movement from discharging to charging position when the drive is through the chain and cable. Otherwise, the bars are subjected only to the tension resulting from weights 64. This is highly desirable, because the bars, being under intense heat in some furnaces, at least, might be drawn out and deformed and interfere with the proper functioning of the apparatus. Also, it is obvious that the greater the tensioning weight, the more power will be required to actuate the conveying apparatus.

In Fig. 8 I have illustrated automatic or semi-automatic control means. A two-way valve generally indicated by numeral 100 is provided in the air line 11g. When in its normal position relief is provided for the cylinders 11f to permit the pistons 11h to rise under the weight of the doors to the dotted line position, illustrated in Fig. 8.

For actuation of these pistons reversely, I provide a solenoid 101, illustrated as an extension of the valve stem, and a coil 102 forming a part of the circuit a. This circuit a is connected to the line wires L and has included in it the normally open switch S. The switch proper is connected to a solenoid 105 having a pair of spaced contact bridges 106, 107. A coil 108 coacts with the solenoid 105 and is in the circuit b. This circuit b is divided into the two branch circuits b1, b2. The former includes a pair of spaced contacts which are arranged to be bridged by the contact bridge 106 and terminates at the switch F normally open and leading to the other of the line wires

L. This switch F is intended for manual operation and may be of any suitable construction, being provided to initiate the forward movement of the conveyor moving from charging position, as illustrated in Figs. 1 and 8, to discharging position.

The other branch circuit b2 includes a pair of spaced contacts arranged to be bridged by contact 107 and is in turn divided into two branches b3, b4, the one leading to a double pole switch S2, spring-held in one position to close circuit b3 which leads therefrom to a second normally closed manually operable switch A in turn connected to one of the line wires L. Manual opening of this switch A serves to arrest movement of the conveyor at any time if so desired.

A limit switch S1 is provided which is normally held in open position by means of a coil spring or the like. An arm 110 is carried on the shaft 11c and provided with a pivotally attached depending rod 111 loosely guided at 111a and carrying the pivoted striker 112, which is so mounted upon the rod 111 as normally to lie in striking position to pick up the arm of switch S1 on opening movement of the doors, its pivotal mounting and the inclined face 112a permitting it to ride by the arm of switch S1 on reverse movement. This switch S1 is included in a circuit c leading from one of the line wires L.

The motor 29 is illustrated as of three-phase construction. Line wires Lf are provided for this actuation. A three pole switch M and a similar three pole switch N are provided for control of the operation of this motor 29. The switches M and N are normally open and are of similar construction, the switch M being intended to throw the motor 29 into movement or rotation in one direction, and the switch N arranged for reversal. The switch M, for example, is operatively attached to the stem 115a of solenoid 115 which carries the spaced bridging contacts 116 and 117. A coil 118 is operatively associated with the solenoid 115 and is in circuit c, which is branched to form circuit d with spaced contacts arranged for bridging by member 116. The branch d includes a pair of spaced contacts arranged for bridging by the member 117 and is joined to circuit b4.

Switch N is similar in construction and the wiring arrangement is such that line wires Lf are so connected as to move the motor 29 in one direction when the switch M is closed and to reverse it when switch N is closed, as will be obvious from the diagram to those skilled in the art.

Associated with the conveyor are the pivoted spring-extended striker members 125 and 126, one being located adjacent each end, although other suitable means moving with or synchronized for movement with the conveyor will be suitable, if so desired, and within the purview of my invention.

The poles or blades of switch S2 are so spaced and the switch is so constructed as to be moved to the left, as viewed in Fig. 8, on movement of the conveyor to discharging position, this movement of the switch first serving to open circuit b3 and then to close a circuit e leading from one of the line wires L. Switch S2 moves sufficiently during the final movement of the conveyor to permit striker member 125 to move between the poles, after which the spring resisting means returns switch S2 to its normal position closing circuit b3 and opening circuit e.

A switch O similar to switch M is provided to initiate and maintain forward movement of the lifting motor 56 and similarly a reversing control

switch P, similar to switch N, is provided to effect reversal of the lifting motor 56.

Circuit e is normally closed through bridging contact 136 and includes the magnet 131 associated with the solenoid 132 of switch O, which in turn leads to the complementary line wire L. A branch circuit f is connected to and leads from circuit e to include the normally open spaced contacts which may be bridged for closing the circuit by the second bridging member 133, similar to member 117 of switch M. This circuit f leads to and through a normally closed spring-urged switch S5 and thereafter through the normally closed pole of switch S3 which is spring resisted and similar in construction to switch S2. The circuit is further extended to join circuit b3 leading through arrester or stop switch A to the other line wire L.

On the reciprocable rod 59 are provided a pair of spaced strikers 140, 141, similar in construction and arrangement to strikers 125 and 126. In movement of the rod 59 to the right, as viewed in Figs. 1 and 8, i. e., during the lifting movement of motor 56, striker 140 will pivot to ride by switch S5 without disturbing the same. As the lifting movement is completed, the striker 141 will momentarily open circuit f by actuation of spring resisted switch S3 and shortly thereafter will close the circuit g leading from one of the line wires through the switch S3. As soon as the striker has moved between the two poles or actuated members of switch S2, the latter will be spring-returned to normal position, as illustrated in the drawings.

On the reverse movement of the lifting motor, striker 141 will move out of proximity to switch S3 without disturbing the same, and as the end of the reverse movement of the rod 59 is approached, striker 140 will momentarily open switch S5 and circuit f until striker 140 moves by, whereupon the spring resisted switch S5 will be closed, reclosing circuit f.

Circuit g leads through the contacts normally closed by bridging member 145 of said switch N 45 through solenoid coil 146 to the other line wire. Branch d1 of circuit d includes the spaced contacts which are bridged by the second bridging member 148 of switch N, which is likewise carried on the stem 149a of solenoid 149. A branch 50 circuit h also leads from circuit g to normally open manually-actuated switch R, which in turn is connected to the other line wire.

At the charging end of the furnace is a double pole switch S4 similar to switch S2 and lying in the path of striker 126, which is similar in construction to striker 125 but oppositely arranged. As the conveyor approaches discharging position on its return movement, the pole of switch S3, normally closing circuit b4, is momentarily 55 opened, breaking said circuit, while the other pole or blade is moved into position closing the circuit which I have designated as k, which leads from one line wire L to the control for switch P. The circuit k includes a pair of spaced contacts which are normally closed by bridging member 150 of switch P, and included in the circuit is the solenoid coil 151 which leads to the other line wire L. A branch f1 of circuit f leads therefrom to include a pair of spaced contacts which may be 60 bridged by the second bridging member 152 of the switch P, these contacts being carried by solenoid 153 as in the cases of switches M and O.

When the conveyor has reached charging position striker 126 will lie between the movable 70 poles or blades of switch S4 and the latter will

have been returned by its spring-actuating means to normal position closing circuit b4.

In the operation of the apparatus described, assuming that the conveyor and associated mechanisms are in the position illustrated in Fig. 1, the operator upon temporarily closing the switch F closing the circuit b—b1, may thereafter release the switch which returns to open position. This momentary closing of this circuit excites the magnet 108 sufficiently to lift the solenoid 105 into 10 its upper position wherein circuit b2 will be closed and maintained in closed position, which throws the solenoid 103 into circuit b—b2 and b3. This movement of the solenoid also closes switch S, closing the circuit a which results in opening of 15 the solenoid valve 101 and flow of air to the door cylinders 117 which, as described before, will result in opening movement of both doors, if two are used. As the left hand door is opened, switch S1 is momentarily closed by striker 112 which 20 thereafter rides by the switch permitting it to return to open position. Temporary closure of switch S1 closes circuit c actuating the solenoid 115 which is lifted to close circuit d at the same time breaking circuit e. Closure of circuit d 25 throws the solenoid into circuit comprising a portion of circuit c, circuit d, circuit b4, switch S4, switch S3, circuit b3 and normally closed switch A to the other line wire. The above described movement of solenoid 115 has sufficed to close the 30 three poles of the current supply switch for motor 29, which then rotates to move the conveyor to the left, the open doors having been raised sufficiently to clear the metal packs or other materials on the conveyor. The last described circuit, 35 serving as it does to make the circuit through magnet 118 keeps the switch M closed.

As the conveyor approaches its discharging position, switch S2 is moved by striker 125, as described before, temporarily opening circuit b3, 40 circuit b—b2, thereby breaking the circuit of magnet 108 and permitting the solenoid 105 to drop, thus opening switch S, after which the door operating pistons return under actuation from the weight of the doors to closing position. At 45 the same time, the circuit, which includes b4, switch S4, circuit d and a portion of circuit c, is broken, thereby terminating the excitation of coil 118, permitting the solenoid 115 to drop, thus opening the forward control switch M of 50 conveyor motor 29.

As the conveyor completes its movement to discharging position, striker 125 will also move switch S2 to close the circuit e exciting the coil 131 and closing switch O to start the lifting motor 55. This same movement of solenoid 103 closes the circuit f through switch S5, switch S3, circuit b3 through normally closed switch A and maintains the excitation of coil 131.

The operator is now free to remove or transfer 60 the exposed metal pack or other object during movement of the conveyor motor 56. As rod 59 moves toward its right hand limit of travel, as viewed in Fig. 1, striker 141 will normally open switch S3 to open circuit f and thereby discontinue the excitation of magnet 131 to permit dropping of the solenoid 103 and opening of switch O, which stops the movement of motor 56. 65

Toward the end of the lifting movement, striker 141 will not only break circuit f but momentarily closes circuit g to excite coil 146 and close switch N to reverse conveyor motor 29 returning the conveyor toward and to charging position, during which movement the metal packs or other objects are maintained upon the sup- 70 75 75

porting members out of contact with the conveying means. In other words material to be heated is retained in the furnace while the conveyor moves back to charging position.

5 The final movement of the striker 126 past the actuated blade or pole of switch S4 temporarily closes circuit *k* before the switch S4 is released and moved to normal position by its actuating spring. This temporary closure of circuit *k* excites the coil 151, closing the reversing switch P for motor 53 in a manner which will be obvious from a description of the operation of switches N and O, the auxiliary circuit which includes *f'* being closed to maintain excitation of coil 151.

10

15 The temporary breaking of the normally closed circuit 54 by movement of the switch S4 also terminates the excitation of solenoid coil 146 and permits switch M to open due to the dropping of the solenoid 143, thereby shutting off conveyor
20 motor 29.

As the lifting motor 56 completes its return movement and the rod 59 is moved back toward position illustrated in Fig. 1 for example, striker 148 will contact and temporarily open switch S5 thereafter riding beyond it and permitting its closure by the spring. This temporary opening of switch S5 breaks circuit f-f' and as will be apparent terminates the excitation of coil 151, permitting the opening of the lifting motor reversing switch P, which terminates the return movement of the lifting and supporting means and deposits the material again on the surface of the conveyor.

35 This cycle may be repeated as many times as desired, preferably being initiated in each instance by temporary closing of switch F by the operator.

If it is desired to stop the actuation of the conveying or lifting means at any time, switch A is manually opened temporarily to serve that purpose.

The conveying means may be reversed after it has first been stopped by temporary closure of the manually operated switch R, as will be obvious.

It will be apparent that the controlling circuits and switches may be modified or redesigned to perform the same functions in substantially the same manner, and I do not wish to be restricted to the form shown and described, nor to the specific form and embodiment of my apparatus, otherwise, except as I may be limited thereto by the appended claims properly interpreted relative to the prior art.

What I claim is:

1. In apparatus of the class described, conveying means comprising reciprocable bars movable between rest positions, said bars each being formed of a plurality of pivotally connected sections, a single supporting member for each of said sections, said supporting members being located nearer one end of each of said sections than the other when said sections are in said rest positions.

65 2. In apparatus of the class described, conveying means comprising movable bars, said bars each being formed of a plurality of pivotally connected sections, a single supporting member for each of said sections, said supporting members being located approximately 20% of the length of said sections from one end thereof when said bars are in normal rest position.

70 3. In apparatus of the class described, conveying
means comprising a plurality of bars, each of
said bars being formed of pivotally connected
sections, means to reciprocate said bars between
75 charging position and discharging position and a
single support for each of said bars, said supports

being located each to lie near one end of the section supported thereby when said bars are in either charging or discharging positions.

4. In apparatus of the class described, conveying means comprising bars, means to move said bars, said last named means comprising rotatable sprocket chains and flexible members, said chains and flexible members extending between and operatively secured to opposite ends of each of said bars.

5. In apparatus of the class described, conveying means comprising bars, means to move said bars, said last named means comprising rotatable sprocket chains and flexible members, said chains and flexible members extending between and operatively secured to opposite ends of each of said bars, means to tension said actuating means, and means to reduce the tension on said actuating means in one direction of movement.

6. In apparatus of the class described, conveying means comprising a plurality of bars, a chain attached at one end to each of said bars and at the other end to a flexible member, the opposite end of said flexible member being operatively attached to the opposite end of said bar, a sprocket engaging said chain, and means to actuate the same in either direction to reciprocate each of said bars between charging and discharging positions.

7. In apparatus of the class described, conveying means comprising bars, means to reciprocate the same between charging and discharging positions, said last named means including flexible driving members, a tensioning means associated with each of said flexible members, and means to reduce the tension on said flexible members in one direction of travel of said conveyor bars.

8. In apparatus of the class described, conveying means comprising bars, means to reciprocate the same between charging and discharging positions, said last named means including flexible driving members, a tensioning means associated with each of said flexible members and means to reduce the tension on said flexible members in one direction of travel of said conveyor bars, said last named means comprising a relatively movable weight carried by said tensioning means, a lifting member operatively attached thereto, and means including a source of power to actuate said lifting member whereby said weight can be lifted out of tensioning position. 40 45 50

9. In apparatus of the class described, conveying means, means to reciprocate the same between charging and discharging positions, said last named means comprising a flexible driving member, a tensioning means associated with said flexible member and including a weight, a lifting member operatively associated with said weight, supporting members movable from inoperative position beneath the upper plane of said conveying means to and from a position lying thereabove wherein material on said conveying means will be lifted out of contact therewith, means to move said supporting members between said positions, said last named means including a member operatively connected to said weight lifting member, whereby when said supporting members are moved to supporting position said weight will be released to move to tensioning position. 55 60 65

19. In apparatus of the class described, a conveyor member, means to move the same between charging and discharging positions, said last named means including a flexible drive member and pulleys engaging the same, one of said pulleys being provided with a depending weight, 75

lifting means comprising a link engaging said weight, a bell crank engaging said link, and a connecting rod engaging said bell crank and means to move said connecting rod axially in either direction to effect lifting of said weight out of depending relation from said pulley or to return the same thereto.

5 11. In apparatus of the class described, conveying means comprising reciprocable members, 10 means to reciprocate the same, weights associated with said members and exerting a force thereon,

means to render said weights inoperative during movement of said members in one direction.

12. In apparatus of the class described, reciprocable conveying members, weights, flexible members operatively interposed between said weights and said members to transmit pull from the former to the latter, and means to render said weights inoperative during movement of said members in one direction.
